UNITED STATES PATENT OFFICE.

JOHN L. PREO AND ISABELLE HENNE, OF BROOKLYN, NEW YORK, ASSIGNEES TO
UNITED SHOE MACHINERY CORPORATION, OF PATERSON, NEW JERSEY, A CORPO-
RATION OF NEW JERSEY.

WORKHOLDING MECHANISM FOR SHOE MACHINES.

Application filed July 6, 1922. Serial No. 573,233.

This invention relates to work supports for shoe machinery, and particularly to mechanism for supporting shoes while operations are performed upon their sole or heel portions.

When performing certain operations upon the sole of a shoe, after the sole has been attached to the upper, it is desirable or essential to provide means for supporting the shoe so that the upper may be completely protected against injury from the tools operating on the sole and the sole may be properly positioned and supported for the work of an operating tool. The operation of the heel seat fitting machine shown in applicants' co-pending application, Serial No. 537,394, filed February 18, 1922, of which the present application is a continuation in part, is an example of this.

An object of the present invention is to provide an improved work supporting mechanism arranged firmly to hold a shoe for an operation such as the heel seat fitting operation above-referred to, although it is to be understood that the invention is not limited to incorporation in a machine of the type set forth in said application or to use in connection with the performance of heel seat fitting operations.

In accordance with a feature of the invention, one part of the work support which is movable both toward and away from the operator and vertically in the machine, is provided with novel retaining and actuating means. In the particular arrangement which has been illustrated, the work support is slidable in a tiltable mounting block. When the work support is vertical, having been pushed back into operative position, it is operatively connected with mechanism for adjusting it vertically and is automatically held against movement in one direction, as illustrated, against downward movement. When the work support has been tilted forward for the removal and replacement of the work, the arrangement is such that the support is automatically unlatched and moved downwardly ready for readjustment as a new piece of work is inserted.

In the accompanying drawings forming a part hereof:

Fig. 1 is a front elevation of a machine such as disclosed in our application, Serial No. 537,394, embodying the matters of the present invention, the cutting and trimming mechanisms claimed in the other application being omitted;

Fig. 2 is a fragmentary side elevation, showing certain operating parts in one position;

Fig. 3 is a similar view showing these parts in another position;

Fig. 4 is a vertical transverse section on a larger scale, showing a shoe supported, positioned and held;

Fig. 5 shows a portion of Fig. 4 on a still larger scale;

Fig. 6 is a sectional top plan showing the shoe-holder with its jaws open, and with parts broken away to show parts beneath;

Fig. 7 is a similar view showing the shoe-holder closed upon a shoe;

Fig. 8 is a vertical longitudinal section on the line 8—8 of Fig. 7;

Fig. 9 is a vertical section on the line 9—9 of Fig. 7;

Fig. 10 is a sectional side elevation of the shoe support, showing the support tilted forward;

Fig. 11 is a sectional bottom plan of the shoe-holder, on the line 11—11 of Fig. 14;

Fig. 12 is a horizontal section looking downward through a side portion of the frame and adjacent part, on the line 12—12 of Fig. 16;

Fig. 13 is a sectional side elevation of the shoe support on a larger scale, the post being in its upright, raised position;

Fig. 14 is a front elevation of the same;

Fig. 15 is a vertical longitudinal section on the line 15—15 of Fig. 4; and

Fig. 16 is a similar view showing parts in a different position.

The frame of the machine includes spaced side uprights 20, connected by suitable cross members including an angle-bar 21. The uprights are further joined at the top by a bed 23, which bed is formed with a suitable recess 24, open at the front for the accommodation of a shoe 14 and its last 15. Bolted to the bed and forming a part thereof, is a bed-plate 25 having a corresponding recess 26. This

bed-plate has a circular depression or recess 27 in its top around the recess 26.

The circular wall of this recess 27, which is interrupted at the front to correspond with 5 the entrance of the recesses 24, 26, forms part of a bearing for the jaw members or "crease plates" 28, 28 of a shoe-holder (Figs. 4, 6 and 7). These jaw members are of segmental form, their outer edges being formed as the 10 segments of circles of the same radius as the circular bearing 27. Their inner shoe-engaging portions 29 are much reduced in thickness and are tapered to comparatively thin edges, adapted to be introduced into the crevice, commonly 15 termed the "rand crease", between the extension of the sole and the inturned portion 9 of the upper of a shoe, as illustrated more particularly in Fig. 5. The upper surfaces of these portions 29 are horizontal and flush 20 with the horizontal upper surfaces of the forward body portions of the jaw members 28, and their bottom surfaces slope upwardly and inwardly to provide the tapered edges described above. The top surfaces of the rear 25 portions of the bodies of the jaw members behind the shoulders 30 may be advantageously depressed somewhat (see Fig. 8), so as to afford a wider clearance at this region 30 between them and a cutter disclosed in our application aforesaid.

Curved grooves or recesses 31 (Fig. 4) are formed in the top of the jaw members at their outer edges, and a retainer-plate 32, which is secured to the plate 25 and has a circular 35 opening 33 of somewhat smaller diameter than the recess 27, overlies these recessed edges of the jaw members and has a curved tongue 34 engaging the grooves for further bearing and to hold the jaw members at all 40 times solidly horizontal and against any undesired displacement. Thus plate 32, with recess 27 of bed-plate 25, forms a track to guide 45 the engaging portions 29 as they are moved to grip or release a shoe. The engaging portions 29 of the jaws 28 are curved to conform substantially to the sides and back of the shoe; that is to say, these edges (see Fig. 6) form 50 between them a recess having a flaring entrance at the front, sides which are substantially straight or slightly curved, and a curved back end. By oscillating the segments in opposite directions in their rim-bearing or track, the engaging portions 29 are caused laterally 55 to approach and recede in order to engage the rand crease and grip the shoe in the manner indicated, thereby holding it firmly, with the sole exposed for operation, and to release the shoe when the work has been completed. This movement of crease plates or 60 jaws 28 thus provides an angular adjustment about a point in line with and corresponding to the back seam of the shoe into the rand crease of which their thin edges 29 enter. The movement of the jaw members is effected 65 through forwardly diverging links 35, piv-

oted at their rear ends at a common point 36 to an arm 37, passing forwardly in slots 38 in the bed-plate 25 and pivoted at 39 at their forward ends to the under parts of the jaw members 28 to the rear of the center of the 70 circular system.

The arm 37 extends toward one side of the machine from the rear ends of the links 35 and is pivoted at its outer end 40 to the bed 23, the purpose of the arm being to support 75 and guide the rear ends of the links for their forward and rearward movement. The pivot pin 36 projects downward into cam slot 41 in a slide 42, which is guided for movement transversely of the machine in a guide 43 on 80 the bed 23. Movement of the slide in one direction or the other consequently actuates the links forwardly or rearwardly to close or open the jaws, and the angle of the slot to the transverse direction being small, the mechanism is self-holding in any position and against the reaction of the shoe when clamped thereon. The slide is operated through a bell-crank 44 fulcrumed on a fixed bracket 45, with its arms pivotally connected, respectively, to the slide and to a forwardly extending link 47, the latter being pivoted in turn to another bell-crank 50 fulcrumed at 51 on another fixed bracket, this bell-crank being connected by a link 51^a with the rear end 90 of a hand lever 46, which is fulcrumed on a bracket 48 secured to the bed and at its forward end has a handle 49 projecting at the 95 front of the machine.

With this preferred jaw-operating mechanism, the jaws are opened and closed by manual operation, and they are held closed by the engagement of pin 36 in slot 41. Because of the construction of the shoe-holder, it centers and positions the shoe, and holds 105 it firmly in such manner as to present the sole for the action of the trimming and cutting mechanisms disclosed in our other application aforesaid, or for other agencies and at the same time protects the upper.

The shoe last is provided with a socket or thimble and is placed upon a tapered dowel 52 on the upper end of a post or shoe-support 53 (Figs. 10, 13 and 14). Said post at its lower portion passes through a hole in the forward part of a tiltable bearing member or mounting block 54, which is fixed on a transverse rock-shaft 55 extending between the side uprights of the frame. In the upright position the lower end of the post 53 rests upon one arm of a lever 56, which is fulcrumed between its ends on a pin 57 on the frame cross-member 21. The top flange 58 of this cross-member is slotted at 59 to permit the post to pass through and to tilt in the manner illustrated in Fig. 10. A spring 60, connected at one end to a screw 61 on the post and at its lower end to a pin 62 projecting forwardly from the mounting-block 54, tends 115 to pull the shoe-support post downward in 120 the manner illustrated in Fig. 10. A spring 60, connected at one end to a screw 61 on the post and at its lower end to a pin 62 projecting forwardly from the mounting-block 54, tends 125 to pull the shoe-support post downward in 130

the mounting 54. Another spring 63, connected at its opposite ends to the pin 62 on the rockable mounting and a pin 64 on the frame member 21, tends to rock the mounting 54 and shoe-support forwardly. A stop pin 65 on the post limits the downward movement thereof in the mounting-block.

On the under part of the mounting-block is a canting clutch plate 66, containing a clutch loop opening 67, slightly larger than the lower part of the post 53, which passes through it. The rear end of said clutch plate is confined with freedom for slight vertical angular movement between the under side of 15 the body of the mounting-block and a piece 68 bolted thereto and having a ledge 69. A pin 70 secured in the rear end of the clutch plate and projecting downward within a longitudinal slot 71 (Fig. 11) in said ledge prevents lateral displacement. A spring 72 interposed between the clutch plate 66 and the block 54 normally holds the clutch plate tilted slightly away from the mounting-block, so that the diagonally opposite front and rear 25 corners of its clutch loop opening 67 are in gripping relation to the post. The clutch therefore permits free upward movement of the shoe support post but will hold it rigidly at any operative elevation against descent.

The relation between the clutch plate and the underlying flange 58 of the frame member 21 is such that when the shoe-holder is tilted forward to remove the treated shoe and replace it with a fresh one, the forward end of the clutch plate encounters the top of the flange (see Fig. 10), so that the spring 72 is compressed and the clutch plate brought flat against the bottom of the mounting block 54, thereby releasing the grip and permitting the spring 60 to lower the shoe-support until the stop 65 strikes the top of the block. When the shoe is held in the embrace of the jaws 28 of the holder hereinbefore described, the spring 63 is powerless to rock the shoe-support forward out of the recess 24, 26 in the bed. When, however, the holding jaws are opened, the spring 63 asserts itself to rock the support. The relations are such that the clutch plate 66 contacts with the frame member 21 and thereby overcomes the clutch spring 72, so that the clutch is thereby automatically released, permitting the automatic descent of the post 53 under the action of the spring 60. When the shoe-support tilts forwardly, the lower end of the post 53 is carried rearwardly away from the lever 56, as seen in Fig. 10.

Means are provided for actuating the lever 56 to force the shoe-support and shoe upward against the under sides of the blade portions 29 of the holder jaws 28 by spring action, thereby firmly to grip the work against lateral or vertical movement.

In the preferred construction illustrated,

a hand-lever 73^a is fulcrumed for this purpose in the upper part of the fixed frame. The operating arm of this lever projects from a hub 167 which is on the outer end of a rock-shaft 168 that passes through a side frame member 75. A short work arm 169 on the inner end of the shaft and connected by a link 170 with a slideable table 78, related to the trimming mechanism, forming a part of the subject matter of our application, Serial No. 537,394, enables this table to be operated by the same lever that controls the shoe-support or jack. The hub 167 may have a flat portion 171 to cooperate with a sliding flat-end bolt 172 (Figs. 2 and 3) guided in a socket 173 and urged forwardly by a spring 174, an impositive latch being thereby provided for holding the parts in actuated condition.

The arm 169 is also pivotally connected to the forward end of a substantially horizontal, longitudinally movable bar 177 (Figs. 15 and 16), which is guided at its rear end in a slot in a bracket 178. Intermediate between its ends this bar bears a roller 179 which, moving in a predetermined path, acts upon an upwardly curved or inclined camway 180 on a substantially horizontal lever 181, this lever being fulcrumed at its rear end on the frame at 182 and being guided at its forward part by a keeper 183. Forward movement of the bar 177 and its roller 179 thus depresses the lever 181, while rearward movement allows it to rise under the action of a spring 190.

The forward end of the lever is over the upper end of a thrust rod or link 176 which extends downward through an opening 185 in the bed-plate, the lower portion of this rod passing through an opening in the power arm of the lever 56, heretofore referred to. A stout compression spring 174 interposed between a collar 176^a on the rod 176 and the lever 56, acts as a yielding transmission element, so that pulling forward on the hand lever 73^a causes the post 53 of the shoe-support to be forced upward but not by a rigid thrust, which might injure the shoe or displace the jaws 28 of the shoe-holder. Such upward pressure seats the last firmly upon the dowel 52, and presses the turned-in portion of the upper close against the under sides of the jaw blades 29. The clutch 66 by gripping the post 53 against downward movement then preserves this adjustment, and insures solid support for the shoe while being worked upon.

The cam action 177, 179, 180, 181 interposed between the lever 73^a and the shoe-support enables the requisite force to press the shoe upward against the gripper jaws to be applied easily and smoothly by manual operation.

While the preferred form of the invention

has been described in detail, it will be understood that we do not limit ourselves to the precise details of construction, as these may be considerably varied without departing 5 from essentials.

What is claimed as new is:

1. In a machine for operating upon shoes, a frame, a work support movable with respect to said frame toward and away from 10 the operator to allow the replacement of a piece of work and to bring it into operative relation to working elements of the machine, said work support being also movable up and down in the machine, means constructed and 15 arranged to be operatively related to said work support when the same is in operative position with respect to the working elements of the machine for adjusting said work support in a substantially vertical direction, 20 and means movable in a direction other than up and down with the work support toward and away from the operator operative to clamp said work support when it has been moved away from the operator in any position of vertical adjustment to which it may 25 be moved.

2. In a machine for operating upon shoes, a frame, a tiltable mounting block in said frame, a work support carried by said mounting block and arranged for vertical adjustment with respect thereto, means for clamping said work support in any position of vertical adjustment to which it may be moved, and means constructed and arranged 30 to be operatively related to the work support to move the same vertically when and only when the mounting block has been tilted to bring the work support into operative relation to the machine.

3. In a machine for operating upon shoes, a frame, a tiltable mounting block in said frame, a work support carried by said mounting block and vertically adjustable with respect thereto, means for clamping said work support with respect to the mounting block, means for urging the mounting block in one direction to bring the work support out of operative relation to the machine, and means for moving said work support vertically arranged to be disconnected from the work support when the tiltable mounting block is moved to a position to bring the work support out of operative relation to the machine and into position for the interchange of 45 pieces of work.

4. In a machine for operating upon shoes, a frame, a tiltable mounting block in said frame, a work support carried by said mounting block and movable with respect thereto, means urging said work support in one direction with respect to the mounting block, means for locking said work support with respect to the mounting block, means urging the mounting block in one direction to bring the work support toward the operator for 50

the interchange of pieces of work, and automatic means for releasing said locking means to allow the work support to be moved by said first-named means when the same has been brought forward into operative position by the operator. 70

5. In apparatus for operating on shoes, a frame, a shoe-support raisable and lowerable thereon, an operating lever and mechanism operable thereby to raise the shoe-support, said shoe support and said operating mechanism being disconnectible to permit downward movement of said shoe support, and a clutch cooperative with the shoe-support to sustain the same at any elevation. 75

6. In apparatus for operating on shoes, a frame, a shoe-support raisable and lowerable thereon, an operating lever and mechanism operable thereby to raise the shoe-support, said mechanism including a yielding spring transmission element, and a clutch cooperative with the shoe-support to sustain the same at any elevation. 85

7. In apparatus for operating on shoes, a frame, a forwardly and rearwardly rockable mounting therein, a shoe-support rockable with said mounting and having a stem 90 slidable up and down therein, an actuating member mounted on a relatively stationary part of the frame to thrust said stem upward, the stem being removed from said member when the support is tilted forward, a clutch carried by the mounting for sustaining the shoe-support at any elevation. 95

8. In apparatus for operating on shoes, a frame, a forwardly and rearwardly rockable mounting therein, a shoe-support rockable with said mounting and having a stem 100 slidable up and down therein, an actuating member mounted on a relatively stationary part of the frame to thrust said stem upward, the stem being removed from said member when the support is tilted forward, a clutch carried by the mounting for sustaining the shoe-support at any elevation, and means whereby 105 said clutch is automatically released when the shoe-support is tilted forward. 110

9. In apparatus for operating on shoes, a frame, a forwardly and rearwardly rockable mounting therein, a shoe-support having a 115 stem slideable up and down in said rockable mounting, an actuating member mounted on a relatively stationary part of the frame to thrust said stem upward, the stem being removed from said member when the support is tilted forward, a clutch carried by the mounting for sustaining the shoe-support at any elevation, means whereby said clutch is automatically released when the shoe-support is tilted forward, and a spring for tilting the mounting and support forward and thereby causing release of the clutch. 120

10. In apparatus for operating on shoes, a frame, a forwardly and rearwardly rockable mounting therein, a shoe-support having a 125

stem slidable up and down in said rockable mounting, an actuating member mounted on a relatively stationary part of the frame to thrust said stem upward, the stem being removed from said member when the support is tilted forward, a canting clutch plate on the under part of the rockable mounting having a clutch opening through which said stem passes, and a relatively stationary abutment on the frame below the clutch-plate positioned to be encountered by said plate when the mounting and shoe-support are tilted forward automatically to release the clutch.

11. In apparatus for operating on shoes, a frame, a forwardly and rearwardly rockable mounting therein, a tiltable shoe-support having a stem slidable up and down in said rockable mounting, an actuating member mounted on a relatively stationary part of the frame to thrust said stem upward, the stem being removed from said member when the support is tilted forward, a clutch carried by the mounting for sustaining the shoe-support at any elevation, and a spring urging the shoe-support downward.

12. In apparatus for operating on shoes, a frame, a forwardly and rearwardly rockable mounting therein, a tiltable shoe support having a stem slidable up and down in said rockable mounting, an actuating member mounted on a relatively stationary part of the frame to thrust said stem upward, the stem being removed from said member when the support is tilted forward, a clutch carried by the mounting for sustaining the shoe-support at any elevation, a spring urging the shoe-support downward, and means whereby said clutch is automatically released when the shoe-support is tilted forward.

13. In apparatus for operating on shoes, a frame, a forwardly and rearwardly rockable mounting therein, a shoe-support having a stem slidable up and down in said rockable mounting, an actuating member mounted on a relatively stationary part of the frame to thrust said stem upward, the stem being removed from said member when the support is tilted forward, a clutch carried by the mounting for sustaining the shoe-support at any elevation, a spring urging the shoe-support downward, means whereby said clutch is automatically released when the shoe-support is tilted forward, and a spring for tilting the mounting and support forward and thereby causing the release of the clutch.

14. In a machine for operating upon shoes, a work support, and means for moving said work support comprising a member provided with a cam surface and a roller guided for movement in a predetermined path and arranged to engage said cam surface, and means for moving said roller along said cam surface thereby to effect a gradual

movement of the work support toward the operating instrumentalities of the machine.

15. In a machine for operating upon shoes, a work support, and means for moving the work support comprising a lever provided with a cam surface, a member provided with a roller arranged to engage said cam surface, means for guiding said roller carrying member for movement in a straight line, and means for moving said member thereby causing said roller to rock said lever and effecting a firm but gradual movement of the work support toward the operating instrumentalities of the machine.

16. In a shoe machine, a frame, a vertically movable shoe-support thereon, an operating lever, a longitudinally movable bar connected with said lever and bearing a cam roll, a cam lever acted upon by said cam roll, and connections including a rod acted upon by said cam lever to actuate the shoe-support.

17. A machine for operating on shoes having, in combination, a frame, a shoe-support raisable and lowerable thereon, an operating lever, connections between the lever and the shoe-support operable to raise the shoe-support upon movement of the lever from its inoperative position, said connections including a yielding spring transmission element, and means for sustaining the shoe-support at any elevation to which it may be raised arranged to release the shoe-support upon the return of the operating lever to its inoperative position.

18. A machine for operating on shoes having, in combination, a frame, a shoe-support carried thereby mounted for forward and rearward rocking movement and having a stem slidable upwardly and downwardly, an actuating member mounted on a relatively stationary part of the frame to thrust said stem upward, the stem being removed from said member when the support is rocked forward, and means for sustaining the shoe-support at any elevation to which it may be raised.

19. A machine for operating upon shoes having, in combination, a frame, a shoe-support mounted for tilting movement toward and from the machine and for sliding movement upwardly and downwardly, an operating lever, connections between the lever and the shoe-support operable to raise the shoe-support upon movement of the lever from its inoperative position, said connections including a yielding spring-transmission element, and means for sustaining the shoe-support at any elevation to which it may be raised arranged to release the shoe-support upon the return of the operating lever to its inoperative position thereby permitting lowering and tilting of the shoe-support.
